UNITED STATES PATENT OFFICE.

DAWSON M. HUMISTON, OF AURORA, ILLINOIS.

SLITTING AND WINDING MACHINE.

1,273,228.

Specification of Letters Patent. Patented July 23, 1918.

Application filed September 8, 1916. Serial No. 119,066.

To all whom it may concern:

Be it known that I, DAWSON M. HUMISTON, a citizen of the United States, residing at Aurora, Illinois, have invented certain new and useful Improvements in Slitting and Winding Machines, of which the following is a specification.

A principal object of the invention is to adapt slitting mechanism especially for slitting abrasive material. Another object is to arrange cutting-off mechanism to coöperate with the slitting mechanism. Another object is to provide means for winding the slit material or strips in containers. Another object is to make the winding mechanism interchangeable with the cutting-off mechanism.

Another object is to generally improve and simplify mechanism of this class. The objects and advantages of the invention will be further pointed out so far as is necessary in connection with a detailed description of the accompanying drawing, which shows one exemplifying embodiment of the invention.

It is to be understood, however, that the invention is capable of embodiment in other forms, and I do not limit myself to details except as claimed.

Figure 1 is a side elevation of a machine embodying the invention, the winding mechanism which may be substituted for the cutting-off mechanism being shown in dotted lines.

Fig. 2 is a top plan of the same.

Fig. 3 is a section in a longitudinal vertical plane of the machine through the slitting rolls and cutter.

Fig. 4 is an enlarged sectional detail of the slitting rolls and guide adjacent thereto.

Fig. 5 is a detail of the winding mechanism in side elevation.

Fig. 6 is a fragmentary detail of the same in rear elevation, parts of the containers being, however, shown in section.

Fig. 7 is an enlarged detail of one of the winding containers, certain adjacent parts being shown in section.

Fig. 8 is a similar detail from an opposite point of view.

Fig. 9 is another enlarged detail of the winding mechanism in side elevation.

Fig. 10 is another fragmentary detail in rear elevation.

Fig. 11 is an enlarged view, mostly in side elevation, of one of the containers, a part, however, being shown in section.

Fig. 12 is a section of one of the containers in the plane of its axis, the cover being shown in place.

Fig. 13 is a sectional detail of the container filled with a wound strip of material produced by the slitting machine, showing means for fastening the strip.

A suitable frame 1 carries on brackets 2, at the feed end, reels 3, on which the material to be slit, of any desired width and length, is carried. This machine is especially designed for cutting abrasive material such as emery cloth or sand cloth, or possibly such material as emery paper or sand paper. It will be sufficient to describe the machine as arranged for cutting emery cloth of the kind used by dentists for treating teeth. It is desired to slit this material into narrow strips, usually a quarter of an inch or less in width, and of various lengths, or to wind the long, narrow strips upon containers, from which they may be conveniently unwound and cut off in any desired lengths by the consumer.

This material 4 from the two feed reels is conducted with its abrasive surfaces together or inward to the slitting rolls 6. These rolls may be of composite construction consisting of alternating disks of different diameter, but however constructed, they provide cutting flanges 7 separated by spaces, and the two rolls are arranged so that the cutting flanges of each fit the spaces between the flanges of the other. Fig. 4 shows the two webs of material passing together into contact with the slitters and shows that alternate parts of the webs as they are slit are forced more or less into the spaces of the two cutting rolls. The fact that the abrasive surfaces are kept together and inward with the clean surface of the cloth outward, serves to protect the cutting edges of the slitters from wear as much as possible.

There is a tendency for the slit strips to stick in the spaces of the slitting rolls and to be drawn around by the rolls, and to

obviate this tendency a guide 8 is provided. This is secured at the ends to side members of the frame and consists of a piece of thin metal, the forward ends of which are slit to correspond with the spaces of the slitting roller. Fingers 9 are thus formed and these are bent alternately up and down, so that one finger lies within the space between each two cutting flanges of each roller, and the forward end of each finger extends nearly to the bottom of this space. Consequently, as the slit strips 4^a are drawn away from the slitting rollers by the appropriate feeding mechanism, the fingers 9 pull the strips out of the grooves of the rollers and alternate pairs of strips pass above and below the guide 8, as clearly indicated in Fig. 4.

To the rear of the guide are feed rolls 10. All the strips come together at the rear of the guide and are propelled by rolls 10 to a suitable cutting off mechanism or winding mechanism. The cutting off mechanism is shown in position in Fig. 3 and consists of a weighted cross member 11, suitably guided for vertical motion in frame members 12. This weighted member carries a knife 13 co-operating with a stationary knife 14 carried by a frame member 15. The transverse member 11 is reciprocated vertically by mechanism later described, and the speed of the reciprocation may be varied. The knife 13 chops off the strips in different desirable lengths as they are fed to the cutting off mechanism, and these strips may fall upon any suitable receiving table (not shown) and may be arranged and packed by hand. Winding mechanism which may be substituted for the cutting off mechanism will be described later.

Various parts of the mechanism so far described are driven as follows: A suitable motor 16 is carried on a part of the frame and drives a longitudinal shaft 17 by suitable belt or other gearing 18. A worm 19 at the rear end of shaft 17 drives a worm gear 20 carried by a shaft 21. Gear 20 rotates a spur gear 22, which may be removable, and co-operates with a pinion 23 carried by an adjustable sector 24. Pinion 23 meshes with a gear 24^a connected with the shaft of one of the slitting rolls 6 and gear 24^a in turn meshes with another gear 25 carried by the shaft of the other slitting roll. By changing gear 22 and adjusting pinion 23, drive ratio of the slitting rolls may be changed. The feed rolls 10 may be propelled by pulleys and a belt 26 from one or both of the slitting rolls, as most clearly shown in Fig. 3.

To the rear of the slitting rolls is a gear 27 which carries or is fixed to, a cam disk having a cam notch 28. Gear 27 is driven by a gear 29 mounted on an adjustable arm 30. This gear 29 drives gear 27 and the cam

by engagement with gear 25 of the lower slitting roll, and by changing gear 27 and gear 29, or both, and adjusting the carrying arm 30 of gear 29 the drive ratio of the cam disk may be varied. An arm 31 is fulcrumed at 32 on the frame and one end is provided with a cam follower 33 to co-operate with cam notch 28. The other end of arm 31 engages a roller 34 carried by cross member 11 of the cutting mechanism. When cam notch 28 comes opposite cam follower 33, the cross bar 11 drops by gravity and cuts the strips. The slant face of the cam notch then strikes the cam follower and moves arm 31 so as to raise the cross bar 11 and knife into position for another stroke.

Winding mechanism which may be employed to wind the slit strips in containers, is indicated in dotted lines in Figs. 1 and 2, and is shown in sufficient detail in Figs. 5 to 13. This mechanism has side frame members 35 provided with drilled holes 36, by which the winding frame members may be secured to the main frame by suitable bolts 37, as indicated in Fig. 1. The frame members 35 revolvably support, in suitable bearings, a plurality, conveniently three, winding shafts 38. Each of these shafts has a slit 39 running from one end to a point 40 near the other end. The slotted ends of the shafts may be made accessible by hinging the adjacent frame piece 35 at 41, as indicated in Fig. 2. But the bearing mounting of the opposite ends of the shafts in the other frame member 35 may be made permanent, if desired. Upon each of the shafts 38, when the hinged frame member 35 is swung out, may be placed a suitable plurality of containers 42 (Fig. 6). These may be substantially in the form of a shallow box apertured to fit the shaft. At one point in the periphery of each of the containers is a slot 43. As the containers are placed on the shafts the slit strips 4^a are separated and the end of one strip is threaded through the slot 43 of one of the containers and then through the slit 39 of the shaft 38. When enough containers are set up and threaded to accommodate all of the strips, the movable frame member 35 is put in position. The containers are then held from turning and at the same time suitably spaced on their shafts by pins 44 carried by cross bars 45 and engaging holes 46 provided in the containers. More than two winding shafts are usually provided for the reason that the necessary width of the containers would make it inconvenient or impossible to place enough containers on two shafts to accommodate all of the strips, or to do so without considerable lateral distortion of the strips.

The winding shafts should be yieldably driven to allow for the varying rotary speed as the diameter of the wound strip within

the spools increases, and this may be done by yieldable gearing or weight mechanism, or spring mechanism. The present embodiment shows spring mechanism for this purpose. A spring 47 with winding and ratchet mechanism 48 of usual clock type, or other suitable type, is provided, and the drive spring is operatively connected to the winding shaft by step-up gearing 49 of suitable ratio. Usually a double multiplying gear arrangement is desirable, as shown. A part of this multiplying gearing may carry a disk 50 and the disk may be provided with a movable stop 51 to engage a frame member 51^a and hold the spring mechanism inactive while the parts are being prepared for winding. Everything being ready and the drive motor 16 of the slitting mechanism being started, the stop 51 is removed and the spring mechanism then rotates the winding shafts 38 and yieldably drives these shafts which wind up the strips within the stationary containers until the containers are filled. The slitting and spring mechanism are then stopped; the containers are removed from the shafts, and in this removal the inner ends of the strips pass out freely through the slits 39 of the shafts. The winding shafts are then loaded with another set of containers, and so on.

Covers 52 are preferably provided for the containers as shown in Figs. 11 to 13, these having slotted hubs 53 which are adapted to spring into the central apertures of the containers and thus to retain the covers in position. At the same time the slots 54 of the hubs accommodate the inner ends 55 of the strips. The covers 52 may be conveniently recessed at 56 to accommodate the edge of the side wall 57 of the containers and the periphery of the cover may preferably continue at some little distance beyond the container as at 58. The covers 52, as shown in Figs. 11 and 12 of the drawing, are not used during the winding operation but are only put in position after the containers 42 have been filled with strips. The outer end 59 of the strip may be brought out through a slot 60 in the peripheral wall 57 of the container and may be secured by a finger 61 formed as a part of the cover 52 and bent down as shown in Fig. 13 to clamp said end 59 of the strip against the peripheral wall of the container. When it is desired to unwind a part of the strip from the container the outer end 59 is freed from the clip 61; the periphery 58 of the cover is grasped in one hand and the strip is then pulled out through the slot 60 to the desired extent and cut off. Evidently many different forms of containers and covers may be used but in the best form of the invention the container mechanism will usually embody the described advantages in some form or other.

While I have described my invention as adapted for the handling of a certain kind of material, it is evident that some or all of the features of the invention are adaptable to handling other material and I do not limit myself as to the use of the invention except as it may be limited by its own characteristics.

I claim:

1. In slitting mechanism, the combination with rolls for holding and feeding a web, of a slitting couple, consisting of rollers having interfitting cutting flanges and grooves, a guide plate posterior to the slitting rolls having fingers extending into the grooves thereof to free the strips therefrom so that alternate strips pass above and below the guide plate.

2. In slitting mechanism, the combination of two rolls for holding material to be slit, means for associating the webs of material from each roll and feeding them together, a slitting couple consisting of rollers having interfitting cutting flanges and grooves, and a guide plate posterior to the slitting rolls having fingers extending into the grooves thereof to free the strips therefrom so that alternate pairs of strips pass above and below said guide plate.

3. In slitting mechanism, the combination of holding reels for two webs to be fed together, a slitting couple to cut the webs simultaneously into strips, means for carrying the strips away from the slitting couple, and means for cutting the strips into lengths, said last named means including a fixed cutter, a movable weighted cutter-bar, a lever, a cam, and cam-driving means to operate the lever in definite relation to the travel of the strips.

4. In slitting mechanism, the combination of means for feeding and slitting one or more webs of fabric, and winding mechanism comprising a plurality of winding shafts, a plurality of independent containers removably placed on one or more of said shafts, means for winding slit strips of fabric within the containers, and means for holding the containers stationary during winding while the shafts revolve.

5. In slitting mechanism, the combination of means for feeding and slitting one or more webs of fabric and winding mechanism comprising a plurality of winding shafts, containers removably placed thereon, means for winding slit strips of fabric within the containers, and means for holding the containers stationary during winding.

6. In slitting mechanism, the combination of means for feeding and slitting one or more webs of fabric and winding mechanism comprising a plurality of winding shafts, containers removably placed thereon, means for winding slit strips of fabric within the con-

ainers, means for holding the containers stationary during winding, and means for yieldably driving the winding shafts.

7. In slitting mechanism, the combination of reels for holding two rolls of fabric, two slitting rolls having interfitting slitting flanges, means for feeding webs of fabric from the reels in contact with each other to

the slitting rolls, and winding mechanism comprising shafts, separate containers removably placed on said shafts, means for securing the ends of slit strips within the containers and winding the strips within the containers, and driving means for the shafts. 10

DAWSON M. HUMISTON.
